UNITED STATES PATENT OFFICE

127,556

DESIGN FOR A DRESS

Clare Potter, West Nyack, N. Y.

Application May 7, 1941, Serial No. 100,814

Term of patent 3½ years

To all whom it may concern:

Be it known that I, Clare Potter, a citizen of the United States, residing in West Nyack, in the county of Rockland and State of New York, have invented a new, original, and ornamental Design for a Dress, of which the following is a specification, reference being had to the accompanying drawing, forming part thereof,

I claim:

The ornamental design for a dress, substantially as shown.

CLARE POTTER.
